WILLIAM S. PYRAH, OF OLD TRAFFORD, ENGLAND, ASSIGNOR TO WESTINGHOUSE ELECTRIC AND MANUFACTURING COMPANY, A CORPORATION OF PENNSYLVANIA.

COMMUTATOR-CYLINDER FOR DYNAMO-ELECTRIC MACHINES.

1,224,206.

Specification of Letters Patent.

Patented May 1, 1917.

Application filed March 24, 1915. Serial No. 16,801.

To all whom it may concern:

Be it known that I, WILLIAM S. PYRAH, a subject of the King of Great Britain, and a resident of Old Trafford, in the county of 5 Lancaster, England, have invented a new and useful Improvement in Commutator-Cylinders for Dynamo-Electric Machines, of which the following is a specification.

My invention relates to commutator cylinders for dynamo-electric machines, and it 10 has for its object to improve the construction of such devices in order that the development of displaced conducting segments commonly known as "high bars," and similar 15 irregularities on the surface of the cylinder may be prevented.

In the manufacture of commutator cylinders, the alternate conducting and insulating segments are assembled together to 20 form a ring or cylinder and are held in position by metal rings of V-shape in cross-section located at each end which engage correspondingly shaped notches in the ends of the assembled commutator segments. 25 The rings, commonly called "V-rings," are drawn together by the use of through bolts or other suitable means so as to firmly grip the segments of the commutator. In order to prevent the occurrence of short-circuits, 30 insulating means must be interposed between the ends of the segments and the metal V-rings, and the best material for this purpose is built-up mica which is formed of scales of mica held together by a suitable 35 binder, such as shellac varnish. It is obvious, from the nature of the material, that built-up mica is not a perfectly homogeneous substance but that parts of it are softer than others. In assembling the parts of a 40 commutator cylinder, the assembled segments are placed in position, with a suitable thickness of built-up mica interposed between their ends and the V-rings, and the latter are drawn toward each other through 45 bolts or other suitable means so that the built-up mica is strongly compressed. The periphery of the commutator cylinder is then turned true and, if necessary, may again be trued up before the completed 50 machine is put into actual service. After the machine has been in service, it may be found that the surface of the commutator cylinder has become irregular and that some segments project beyond others, forming

what are commonly known as "high-bars." 55 These irregularities give rise to various difficulties the effects of which are shown in chattering of the brushes and in sparking. The alteration in the form of the commutator cylinder is due to the expansion and 60 contraction of the segments that are caused by variations in temperature and by a lack of homogeneity in the layer of insulation between the ends of the bars and the V-rings on account of which the thickness of the 65 insulation becomes non-uniform. In other words, the contact between the ends of the commutator segments and the built-up mica insulation is largely point-and-line contact instead of surface contact and consequently, 70 some of the segments become loose and are displaced by centrifugal force.

According to the present invention, irregularity and want of homogeneity in the built-up mica insulation is compensated for 75 by inserting between such insulation and the surfaces of the V-rings to which it is applied layers of lead or other suitable material which, although rigid and practically incompressible, has the property of flowing 80 readily under pressure. During the assembly of the commutator cylinder, the pressure applied to draw the V-rings toward each other causes the lead or other material to flow in such a manner as to compensate for 85 the irregularities in the built-up mica insulation. The spaces between the V-rings and commutator segments become completely filled with the material and the compression is substantially uniform at all parts. The 90 result of this is that approximately complete surface contact occurs and is maintained between the ends of the segments and the insulation. It is found that, with this construction, when once the commutator has been trued up, it remains so under 95 all ordinary conditions of service.

The single figure of the accompanying drawing is a longitudinal sectional view of 100 a portion of a commutator cylinder constructed in accordance with my invention.

The sleeve or bushing 1 on which the commutator cylinder is built up is secured to the shaft of the machine in any suitable manner, and a plurality of segments 2, provided with V-shaped notches 3 in the ends thereof, are held in position by the V-rings 4 which engage the notches 3 and are drawn

toward each other by a plurality of through bolts 5 or any other suitable means disposed at intervals around the face thereof. The V-rings 4 are insulated from the commutator segments 2 by layers 6 of built-up mica insulation, which are separated from the V-rings by sheets 7 of lead or other similar material that is practically incompressible but which flows readily under pressure. In order to prevent the metal from flowing out at the ends of the segments, by reason of the pressure, it is preferably located in recesses 8 that extend over nearly the whole of the surface of each V-ring which is in contact with the ends of the commutator segments.

The lead or other material may be applied to the surface of the V-ring in any suitable manner. It may be spun or beaten to form, or a number of sheets of lead of suitable size may be placed side by side around the V-rings before the built-up mica insulation is applied thereto, or it may be cast into the recesses 8 provided in the V-rings 4 by means of a suitable mold.

In the place of lead, other metals or alloys having somewhat similar properties may be utilized in the present invention, and the improved construction is also applicable to commutator cylinders in which insulation of a non-homogeneous kind, other than mica, is used.

While I have shown my invention in a simple and preferred form, it is not so limited but is susceptible of various modifications of structure and arrangement of parts within the scope of the appended claims.

I claim as my invention:

1. A commutator cylinder for dynamo-electric machines comprising a plurality of assembled conducting and insulating segments, retaining means that are adapted to engage said segments, insulating means interposed between said retaining means and said segments, and further means interposed between said retaining and insulating means for preventing displacement of said conducting segments.

2. A commutator cylinder for dynamo-electric machines comprising a plurality of assembled conducting and insulating segments, a plurality of V-rings that are adapted to retain said segments in position, insulating means interposed between said V-rings and said segments, and further means interposed between said V-rings and said insulating means for preventing displacement of said conducting segments.

3. A commutator cylinder for dynamo-electric machines comprising a plurality of assembled conducting and insulating segments, a plurality of V-rings that are adapted to retain said segments in position, a plurality of layers of built-up insulation between said V-rings and said segments, and

means interposed between said V-rings and said built-up insulation for preventing displacement of said conducting segments.

4. A commutator cylinder for dynamo-electric machines comprising a plurality of assembled conducting and insulating segments, a plurality of metal V-rings that are adapted to retain said segments in position, a plurality of layers of built-up insulation interposed between said V-rings and said segments, and a plurality of layers of malleable material interposed between said V-rings and said built-up insulation for preventing displacement of said conducting segments.

5. A commutator cylinder for dynamo-electric machines comprising a plurality of assembled conducting and insulating segments, a plurality of metal V-rings that are adapted to retain said segments in position, a plurality of layers of built-up insulation interposed between said V-rings and said segments and a plurality of layers of soft metal interposed between said V-rings and said built-up insulation for preventing displacement of said conducting segments.

6. A commutator cylinder for dynamo-electric machines comprising a plurality of assembled conducting and insulating segments, a plurality of metal V-rings that are adapted to retain said segments in position, a plurality of layers of built-up insulation between said V-rings and said segments and a plurality of layers of lead interposed between said V-rings and said built-up insulation for preventing displacement of said conducting segments.

7. A commutator cylinder for dynamo-electric machines comprising a plurality of assembled conducting and insulating segments, a plurality of metal V-rings that are adapted to retain said segments in position and are provided with recessed portions adjacent to said segments, a plurality of layers of soft metal disposed in said recessed portions, and a plurality of layers of built-up insulation interposed between said V-rings and said segments.

8. A commutator cylinder for dynamo-electric machines comprising a plurality of assembled conducting and insulating segments, a plurality of metal V-rings that are adapted to retain said segments in position and are provided with recessed portions adjacent to said segments, a plurality of layers of lead disposed in said recessed portions, and a plurality of layers of built-up mica interposed between said V-rings and said segments.

9. A commutator cylinder for dynamo-electric machines comprising a plurality of assembled conducting and insulating segments, a plurality of metal V-rings that are adapted to retain said segments in position and are provided with recessed portions ad-

5 jacent to said segments, a plurality of layers of lead molded in said recessed portions and a plurality of layers of built-up insulation interposed between said V-rings and said segments.

In testimony whereof, I have hereunto

subscribed my name this 25th day of February, 1915.

WILLIAM S. PYRAH.
